UNITED STATES PATENT OFFICE.

SILAS M. EVANS, OF SAND SPRINGS, OKLAHOMA.

DESIGN FOR A SODA WATER CARRIER OR SIMILAR ARTICLE.

Application filed February 6, 1928. Serial No. 25,247. Term of patent 3½ years.

To all whom it may concern:

Be it known that I, SILAS M. EVANS, a citizen of the United States of America, residing at Sand Springs, in the county of Tulsa, and State of Oklahoma, have invented a new, original, and ornamental Design for Soda Water Carrier or Similar Article, of which the following is a specification, reference being had to the accompanying drawing, forming part thereof.

Figure 1 is a perspective view of a soda water carrier, showing my new design; and Figure 2 is a side elevational view of the same.

I claim:

The ornamental design for a soda water carrier or similar article, as shown.
